UNITED STATES PATENT OFFICE.

PETER F. THEDE, OF CHICAGO, ILLINOIS, ASSIGNOR TO THE GENERAL PNEUMATIC COMPANY, OF CHICAGO, ILLINOIS, A CORPORATION OF ILLINOIS.

APPARATUS FOR CONVERTING, STORING, AND UTILIZING WIND-POWER.

SPECIFICATION forming part of Letters Patent No. 690,794, dated January 7, 1902.

Application filed January 30, 1901. Serial No. 45,357. (No model.)

To all whom it may concern:

Be it known that I, PETER F. THEDE, a citizen of the United States, residing at Chicago, in the county of Cook and State of Illinois, 5 have invented new and useful Improvements in Apparatus for Converting, Storing, and Utilizing Wind-Power, of which the following is a specification.

My invention relates to apparatus for converting, transmitting, and utilizing the power of the wind by means of successive compressions of air to attain the same in a high state of compression for utilization for any desired purpose.

15 The invention consists in certain features and details of construction and combinations of parts, which will be hereinafter more fully described and claimed.

In the drawing forming part of this specification the figure thereof is a diagrammatic view illustrative of my invention.

I have shown in the drawing three wind-motors 1 2 3, the same being of any suitable or preferred form and construction and located at intervals apart. I prefer that each of said motors be separated from the next adjacent ones by a distance of approximately two hundred feet. While three of these motors have been shown, it is obvious that a 30 greater or less number may be employed.

The motor 1 is connected with and operates an air-compressor 4 of any suitable or preferred construction, the motor 2 is connected with and operates an air-compressor 5, and the motor 3 is connected with and operates an air-compressor 6. The connection between each of said motors and the air-compressor which each operates is by way of a vertical shaft 7, driven from the power-wheel 8 and having a pinion 9 upon its lower end which meshes with a pinion 10 on a horizontal shaft 11. The said shaft 11 is provided with a drum or pulley 12, around which passes a belt 13. Said belt also passes around a wheel 45 or pulley 14, mounted on a counter-shaft and connected with the piston-rod 15 of the air-compressor. The inlet-opening 16 of the compressor 4 communicates with the atmosphere, and the compressors 4 and 5 are connected 50 by a pipe or conduit made up of the sections

17 and 18, with the air-receiver 19 interposed between them. Adjacent to the point of entrance of the pipe or section 18 with the compressor 5 the same is provided with a cut-off valve 19^a. Connecting the compressors 5 and 6 is a pipe or conduit made up of the sections 20 and 21, with an air-receiver 22 between them. Adjacent to the point of connection of the pipe 21 with the compressor 6 is a cut-off valve 23. Leading from the discharge 60 end of the compressor 6 is a pipe or conduit 24, which communicates with a storage tank or container 25, into which the compressed air is finally delivered and from which it is discharged for any suitable purpose. As the 65 different wind-motors 1, 2, and 3 are separated by a distance of approximately two hundred feet, the communicating pipes between the different compressors 4, 5, and 6 and between the compressor 6 and the storage-tank 70 25 are also approximately two hundred feet in length.

In operating my improved apparatus the valves 19^a and 23 are first closed and then the wind-motor 1 is started. This action causes 75 the compressor 4 to be actuated, the same drawing in atmospheric air through the inlet 16 and compressing the same, so that it is raised to, say, twenty pounds gage-pressure. This air passing from the compressor 4 fills 80 the connections 17, 18, and 19 between the compressors 4 and 5, and as the said connections 17, 18, and 19 are exposed to the outside currents of atmospheric air the heat generated by the compression in the compressor 4 85 is quickly dissipated or absorbed, with the result that when the air under pressure reaches the valve 19^a, adjacent to the compressor 5, it has been lowered down to the temperature of atmospheric air. Any moisture that may be contained in the compressed air from the compressor 4 is precipitated and trapped in the air-receiver 19, from which it may be drawn off by any suitable means. As soon as the connections between the compressors 4 and 5 have been filled with air at 90 twenty pounds gage-pressure, or thereabout, the motor 2 is thrown into operation and the valve 19^a is opened. The air at twenty pounds gage-pressure is then admitted to the second 95 100

compressor 5, where it is subjected to a second compression and raised to, say, fifty pounds gage-pressure. Passing from the compressor 5 the air enters the connections 5 20, 21, and 22 between the compressors 5 and 6 until these connections are filled with air at fifty pounds gage-pressure, or thereabout. In passing from the compressor 5 to the valve 23 in the pipe-section 21—a distance of two 10 hundred feet, or thereabout—the temperature of the air is reduced to that of atmospheric air, and any moisture that may be contained therein is condensed and trapped in the receiver 22, from which it may be drawn off by 15 any suitable means. As soon as the connections between the compressors 5 and 6 are filled with air at fifty pounds gage-pressure the motor 3 is thrown into operation and the valve 23 opened, admitting the air which has 20 been previously compressed into the compressor 6. In this latter compressor it is subjected to an additional compression and raised to, say, eighty-five pounds gage-pressure, and from this compressor it passes through the 25 pipe 24 to the final storage-tank or container 25. As the pipe 24 is subjected to the currents of atmospheric air and as it is of considerable length—approximately two hundred feet—the heat generated by the 30 compression in the compressor 6 is soon dissipated or absorbed and the air in the pipe 24 is reduced to the temperature of atmospheric air.

It will thus be seen that by my apparatus 35 I am enabled to utilize the power of the wind to successively compress atmospheric air and finally obtain the same in a highly-compressed state in the storage-tank or container, from which it may be drawn for utilization for 40 refrigerating purposes, manufacture of liquid air, or driving of compressed-air motors, or for the performance of any other work. Furthermore, by my apparatus I overcome the 45 objection to prior compressed-air apparatus of providing artificial means for cooling the air after each compression. By my apparatus the cooling of the air after the compression thereof is effected entirely by natural means by exposing the conduits through 50 which the air passes to the action of currents of atmospheric air. It should be stated in this connection that the different air-compressors and the different connections between the same, as well as the delivery-pipe 55 24 and the storage-tank 25, are provided with a suitable covering 26 to protect them from the heat of the sun, while permitting them to be acted upon by the currents of atmospheric air.

60 The power-wheel of each second wind-motor is disposed in a higher plane than those upon opposite sides thereof, the difference in height being equal to the diameter of said wheels. The object of this is to provide 65 means whereby the power of the wind when it is blowing in a direct line with the differ-

ent motors will not be intercepted or cut off by those motors which precede any particular one.

By locating the different motors at a great 70 distance apart—at, for example, two hundred feet apart—I provide means not only whereby the connecting-pipes between the different air-compressors may be subjected to the action of atmospheric air throughout the greatest 75 possible extent, but also provide means whereby any currents of air which may be broken up by impinging against one motor may have an opportunity of reuniting before 80 they reach the next motor.

The capacities of the different motors after 85 the first conform to the ratio of increase in the air compression, and the capacities of the air-compressors conform to the capacities of the wind-motors and to the ratio of increase 90 in the air compression in the different stages thereof. The capacity of the connections between the different compressors corresponds with the capacity of the different compressors 95 with which they connect.

While I have shown and described three 100 motors and three air-compressors connected therewith and operated thereby, I do not limit myself to this exact number of these parts, as they may be increased indefinitely or decreased.

An important point of advantage of my construction in which a series of wind-motors is employed is that I am enabled to obtain an immediate accumulation of power, which cannot be done by a single motor, except after 105 an appreciable lapse of time.

Having now described my invention, what 110 I claim as new, and desire to secure by Letters Patent, is—

The combination with a series of wind-motors arranged at great intervals apart, of a series of air-compressors respectively connected with and independently operated by said 115 motors, the first compressor of the series communicating with and drawing in air from the atmosphere, valved connections between each successive pair of said compressors, the said connections being exposed to the atmosphere, a storage-tank located at a distance from the 120 last compressor of the series, a pipe or conduit connecting said storage-tank with said last compressor of the series and exposed to the atmosphere, and a covering for said pipe, said storage-tank and said connections, the 125 said covering being located a short distance above these parts, so as to protect the same, while permitting them to be acted upon by the currents of air.

In testimony whereof I have hereunto set 130 my hand in presence of two subscribing witnesses.

PETER F. THEDE.
